UNITED STATES PATENT OFFICE.

THOMAS A. BOWERS, OF BROOKLINE, MASSACHUSETTS.

DESIGN FOR A WIRE WHEEL.

54,588.

Specification for Design.

Patented Mar. 9, 1920.

Application filed August 26, 1919. Serial No. 320,075. Term of patent 14 years.

To all whom it may concern:

Be it known that I, THOMAS A. BOWERS, a citizen of the United States, residing at Brookline, in the county of Norfolk and State of Massachusetts, have invented a new, original, and ornamental Design for a Wire Wheel, of which the following is a specification, reference being had to the accompanying drawing, forming a part thereof.

The figure is a plan view of a wire wheel, showing my new design.

I claim:

The ornamental design for a wire wheel, as shown.

THOMAS A. BOWERS.
